UNITED STATES PATENT OFFICE

HAROLD L. SEAMAN, OF LONG BRANCH, NEW JERSEY, ASSIGNOR OF ONE-HALF TO
JACOB F. OBERLE, OF NEW YORK, N. Y.

SEA SKIFF

Application filed January 12, 1931. Serial No. 508,227.

This invention relates to improvements in boats and has more particular relation to improvements in hull structures for the so-called "outboard" motor boats or skiffs.

One of the several objects of the invention is to provide a boat of improved structure for allowing a detachable "outboard" motor to be applied thereto so that a part of the motor including the propeller projects 10 through the bottom of the boat, and the whole may be tilted to bring the propeller above the line of the bottom of the boat.

Another object of the invention is to provide a stream line hull which will ride on the 15 water at speed without an undue portion of the bottom of the boat projecting above the water line.

A further object of the invention is to provide a hull so constructed below the water 20 line as to prevent capsizing when turning at high speed.

A still further object of the invention is to provide a hull so constructed as to allow the detachable motor to be projected through its 25 bottom and at the same time prevent the water rising to an undesirable height in the motor "well".

The invention also has further objects, all 30 of which will be hereinafter more particularly set forth and claimed.

In the accompanying drawings forming part of this specification,

Figure 1 represents a side elevation partly 35 in vertical section of a boat embodying my invention.

Figure 2 represents a bottom "plane" view of the same.

Figure 3 represents a rear end elevation of the improved boat.

Generally speaking, "outboard" motor boats have been constructed so that the motor is in reality "outboard" and hangs upon the transom of the boat so that the weight of the motor is at the extreme back end. This method of construction results in the back of the boat being depressed because of the location of the motor and because of high speed so that so much of the forward part of the hull is lifted above the water line as to render the boat "cranky" and unmanageable 40

at high speed. In overcoming such objections the present applicant has brought the weight of the motor within the hull to obviate the tendency to cause the bow to be lifted by the weight of the motor on the rear 55 transom.

He has also curved the back part of the bottom of the boat downward in a stream line which acts as a plane to force the back part of the boat up at speed and thus cause a 60 greater part of the forward portion of the boat to be held down to give the proper displacement for supporting the boat.

Boats of the present sea skiff type when built with round bottoms have a tendency 65 when turning sharply at high speed to roll over, as there is no resistance to the side rolling movement caused by rapidly diverting the hull to one or the other side of a straight course and causing the force of momentum 70 to be exerted transversely of the hull instead of longitudinally. This rolling action exerts its greatest force, of course, where the greatest weight is present in the boat, that is, in proximity to the engine and the operator. 75

To counteract this effect, the present invention provides at that portion of the hull that has the greatest tendency to roll, a structure which resists this rolling action by "plane" surfaces which are at an angle to the 80 rounded surfaces of the remainder of the boat and bear or press directly against the water when the boat has a tendency to roll on its regular rounded bottom.

Further, boats which have heretofore been 85 constructed and which have a motor "well" through which the motor projects out through the bottom of the boat, have had a tendency at high speed to force the water up into the "well" within the boat so that the 90 "well" will almost completely fill and retard the speed.

By the stream line construction of the bottom of the boat in proximity to the well, the present invention in use sets up a "stern 95 wave" when the boat is at high speed that prevents the water rising into the "well" except for a very short distance and thus removes all retarding influences.

Described in detail, the hull of the boat or 100

skiff 1, is of the "clinker" built construction having curved sides and a restricted flat bottom, 1a. The rear portion of this flat bottom 1a is curved downward in a stream line as at 2, to form a slight "plane" at this location to cause the stern to be forced upward at high speed and thus bring the bow of the boat down so that a greater portion of the hull rests upon water and the boat as a whole virtually "planes" over the water.

In order to have the hull naturally rest upon the water farther forward than usual, the bottom 1a is curved down slightly as at 2a forward of the "plane" portion 2; this curve forming a stream line with the "plane" portion with no abrupt breaks in this stream line. The motor 4 is hung in the usual manner by a clamp having thumb-screws on a bulkhead 3 which extends from side to side of the hull the proper distance from the transom 10. Two partition walls 6—6, of the same height as the bulkhead extend from the bulkhead to the transom and thus form the motor "well" 12.

The transom itself is cut out at the bottom so that the rear of the "well" 12 is open to permit any unusual surge of water into the "well", to escape and at the same time to provide an opening through which the motor and propeller can pass when the motor is tilted in the usual manner to bring the propeller above the bottom of the boat for landing on a shore or in shallow water.

When the motor is in position as shown in Figure 1, it will be seen that the propeller 5 extends well below the bottom of the boat and well below the surface of the "stern wave" created by the high forward speed of the boat and its peculiar construction.

Heretofore, in boats having motor wells, the "stern wave" has had a tendency when forced upward partially by the action of the propeller to rise into the motor "well" in a broken mass of water and almost completely fill the "well".

In other words, without applicant's improvements now to be described and with the motor "well" such as shown in Figure 3, the "well" would be completely filled with escaping broken water when the boat was travelling at speed.

To obviate this very undesirable condition I extend the bottom of the boat over the lower part of the well as at 8 to provide two guard plates inclined towards each other at their inner edges. This construction with the stream line "plane" causes the "stern wave" to pass almost directly to the rear with very little upward curve and when the boat is at speed the motor "well" is almost entirely free of water. This action is assisted by the action of the "plane" 2 which forces the stern up into planing position and thus lifts the boat at the rear to prevent "squatting" which

"squatting" would, of course, tend to further fill the motor "well" with water.

As has been before described the usual round bottom boat has a decided tendency when it is turned at high speed to roll over or capsize, and to counteract this tendency the present invention has a hull structure at the rear as at 9 which presents a bearing surface under water that counteracts any tendency to roll, as this rear portion is so curved inward as to really, in effect, form a reverse curve to the curve of the hull.

When the hull develops a tendency in turning to roll, these surfaces 9 form a "scoop" or intensely resistant bearing surface against the water because of this reversed curve to the outer curve of the hull, as best shown in Figure 3.

With this steadyng structure, the skiffs of the present invention may be turned sharply at full speed without any tendency to roll, as the bearing surfaces 9 on the outer side of the boat form a barrier by contact with the water to resist the rolling movement that the remaining round portion of the hull would naturally take.

These boats offer favorable conditions for speed and safety in large and wind tossed bodies of water and have been tested to considerable extent in the Atlantic Ocean off the Jersey coast.

The "planing" effect of the hull, the absence of water in the motor "well" and the stability in making turns have provided a boat of the greatest speed possible according to the 100 horse power employed and such boats have been in actual use as speed boats in speed and reliability tests.

The unusual structure of the bottom of this improved hull with its peculiar stream line from stem to stern, eliminates the usual broken water that reaches the propeller from the form of the boat having abrupt steps or "plane" bottoms, and thus provides an unbroken grip for the blades of the propeller. 110 Further this stream line construction also eliminates the retarding vacuums that form back of the usual abrupt step bottom "planes" and thus makes for greater speed. As these boats are essentially speed boats, the structure adds a number of miles to the speed.

Having thus described my invention, what I claim as new and desire to secure by Letters Patent is:

1. A boat hull having a flat bottom with a bottom "plane" surface at the rear and a forward normal draft greater than the draft at the "plane" surface section and a stream line formation along the entire bottom.

2. A boat hull having a section partially rounded and a flat bottom having a "planing" section at the rear with stream-line connection with the forward part of the flat bottom, the forward normal "draft" being greater than the draft at the "plane" section.

3. The combination with a boat hull having a motor "well" located therein at the rear for the accommodation of a detachable motor of submerged "stern wave" plates at the bottom of the motor "well" to form a "stern wave" below the "well" to lower the water in the well when the boat is at speed.

4. The combination in a boat hull of an exterior rounded upper portion and flat bottom and side rear exterior under water sections extending in a reverse curve to the hull curve to provide a grip or resistance to the "rolling" action of the hull.

5. The combination in a boat hull, of a partially rounded hull having a flat bottom with a "plane" at the rear, of less draft than the forward portion of the hull, and vertical reversely curved sides at the rear to resist "rolling" of the hull in turning.

6. The combination with a hull having a motor "well" with a bottom aperture and a transom aperture of submerged "stern wave" plates over a part of the bottom aperture to force water past the "well" at high speed.

In testimony whereof I affix my signature.
HAROLD L. SEAMAN.
